UNITED STATES PATENT OFFICE.

PETER H. JACKSON, OF SAN FRANCISCO, CALIFORNIA.

FLOOR, SIDEWALK, AND LIKE CONSTRUCTION.

No. 833,461.

Specification of Letters Patent.

Patented Oct. 16, 1906.

Application filed October 12, 1905. Serial No. 282,471.

To all whom it may concern:

Be it known that I, PETER H. JACKSON, a citizen of the United States, residing in the city and county of San Francisco and State of California, have invented new and useful Improvements in Floor, Sidewalk, and Like Constructions, of which the following is a specification.

My invention relates to improvements in the construction of artificial-stone, cement, or concrete floors, roofs, sidewalks, or the like, in which corrugated sheet-metal bottoms form a ceiling to an apartment beneath, part of which may be illuminated and alternate with portions which are not illuminated.

It consists in the construction of sheet-metal concrete-supporting bottoms having varying depths in the illuminating and unilluminating portions.

It also consists in details of construction which will be more fully explained by reference to the accompanying drawings, in which—

25 Figure 1 is a plan view showing a sidewalk with my construction. Fig. 2 is a section through X X of Fig. 1. Fig. 3 is a section through Z Z of Fig. 1. Fig. 4 shows the sidewalk continued to the curb.

30 In Patent No. 725,846, issued to me April 21, 1903, I have shown a means for constructing corrugated-metal bottoms to be used in conjunction with illuminated and unilluminated spaces in which provision is made for a greater depth of concrete or plastic filling 35 over the unilluminated portions by the use of bottoms with similar depths of corrugations but laid at different levels.

In my present invention I obtain the desired result by the employment of bottoms having an unequal depth of corrugations.

40 In the lighting of basements or rooms beneath floors or roofs where there are piers, columns, or walls having openings at intervals through which the light may pass from the front to the inner room to be lighted such lighting is effected by the use of glass inserted in the sidewalk or similar surface. As the glass is an expensive portion of the structure, it is desirable to use the glass only opposite the light-openings above referred to, and it is preferable to make a solid concrete or equivalent flooring in the intermediate portions or opposite the piers or solid portions of the wall.

45 The concrete filling which surrounds the

glass is sufficiently separated by the depth of the glass to prevent its cracking by expansion and contraction; but the deeper solid portion of the concrete must in some way be 60 provided with means to prevent this cracking, such means usually consisting of transverse cuts or incisions made in the surface and dividing it into squares, so that the individual squares may contract and expand 65 with relation to the incisions and the surface of the squares will not be cracked.

In order to make a symmetrical support for the glazed and unglazed portions of the surface, I employ a metal corrugated to 70 form alternate elevations and depressions. The portion A, which coincides with the openings between the piers or through the walls, is provided with glass of any prismatic or other suitable form, through which the light may 75 pass and by which it is diverted through the wall-openings and into the basement extension at the rear. These corrugations are made of suitable depths, as shown plainly at 2 and 5, and the glass being set into the supporting-surface the intermediate spaces are 80 filled with a suitable concrete or Portland cement or other filling up to the level of the top surface of the glass. The small amount of concrete at any particular point between the 85 glasses and the depth of the glasses are such that there is no danger of the cement cracking by expansion or contraction.

The piers or walls 4, which are interposed at intervals along the building-front, will 90 prevent any light passing into the basement where said piers are located, and in order to save expense the portion of the sidewalk or floor corresponding with these piers may be made of solid cement. In order to give the 95 necessary strength to this portion, the corrugations 5 are of considerably less depth than the corrugations where the glass is introduced. By this construction the bottom or all of the bottoms of the corrugations are on 100 a common level and may thus be supported by suitable beams or supports, while the upper surface above the corrugations 5 may be filled with a thicker body of cement, and thus brought up to a level with that portion 105 of the surface which is occupied by the glass. By thus making the corrugated sheet metal of different depths I am enabled to support all portions on the same plane, and the end bearings are also on the same level, thus saving 110 the expense of interposed metal bearers that would otherwise be necessary to adjust

the different thicknesses of the illuminated and non-illuminated sections.

As shown in Fig. 4, 6 is a header-beam, and 5 8 the tail-beam, coped into the header-beam 6, the outer end resting upon the outer retaining-wall, from which the curb also rises. That portion of the sidewalk which is formed 10 of solid plastic material extends between these header-beams, and the shallow corrugated sheet metal is supported upon these beams. That portion in which the glass is fitted has the deeper corrugations, and the outer sides of these corrugated-metal sheets are supported upon the header-beam 6 and 15 upon the same plane with the part previously described. Between the basement-piers extend the angle-iron supports 10. These are of comparatively shallow depth and will not prevent the passage of light 20 and from the glass into the rear portion of the basement. By these improvements I dispense with the connecting-irons, present bottoms of different thicknesses on the same level by using various depths of retaining- 25 channel corrugations and equally supported on the same plane and forming a continuous ceiling for both portions, while the top surface and both of the light and blind portions are on the same level.

30 Having thus described my invention, what I claim, and desire to secure by Letters Patent, is—

1. An improvement in sidewalk, floor and

like structures, said improvement consisting of sections formed of corrugated-metal bottoms of different depths of corrugations having lower surfaces upon the same plane, and a filling of concrete or cement of correspondingly different depths, and having a level upper surface. 35

2. A sidewalk, floor, or like structure composed of corrugated-metal bottoms with different depths of corrugations, the meeting bottom edges of said sections being on the same level, a filling of concrete or cement covering and uniting the corrugations and forming a level wearing-surface at the top. 40

3. A sidewalk, floor, or like structure composed of corrugated-metal bottoms perforated for illuminating lights or lenses, an unperforated corrugated-metal bottom with lesser depth of corrugations than the first-named bottom, said bottoms having their meeting lower edges on the same plane, and the outer edges resting on the same level support, a cement or concrete filling imposed on the different depths of corrugations, and having a common level wearing-surface. 45

In testimony whereof I have hereunto set my hand in presence of two subscribing witnesses. 50
